UNITED STATES PATENT OFFICE.

NATHAN B. LEVY, OF SCRANTON, PENNSYLVANIA.

DESIGN FOR A HAT-PIN.

No. 38,654.

Specification for Design.

Patented July 9, 1907.

Application filed June 7, 1907. Serial No. 377,838. Term of patent 14 years.

To all whom it may concern:

Be it known that I, NATHAN B. LEVY, a citizen of the United States, residing at Scranton, in the county of Lackawanna and State of Pennsylvania, have invented a new, original, and ornamental Design for Hat-Pins, of which the following is a specification, reference being had to the accompanying drawing, forming part thereof.

The drawing is a perspective view of a hat pin showing my new design.

I claim:

The ornamental design for a hat pin as shown.

NATHAN B. LEVY.
